(57) **CLAIM**

The ornamental design for an enclosed building structure, as shown and described.

DESCRIPTION

FIG. 1 is a top-front-left perspective view of an enclosed building structure showing my new design;

FIG. 2 is a bottom-rear-right perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a right elevated view thereof;

FIG. 8 is a left elevated view thereof;

FIG. 9 is a top-front-left perspective view thereof, showing the enclosed building structure with anchors, sprinklers, and a solar panel;

FIG. 10 is a bottom-rear-right perspective view thereof, showing the enclosed building structure with the anchors, the sprinklers, and the solar panel; and,

FIG. 11 is a reduced top-front-left perspective view thereof, showing the enclosed building structure surrounding a residential building.

The broken lines showing of entrances in FIG. 1-11, the broken lines showing of anchors, sprinklers, and a solar panel in FIG. 9-11, and the broken lines showing of a residential building in FIG. 11 are included for the purpose of showing environmental structure and form no part of the claimed design.
